CLAIM

The ornamental design for a display stand as shown and described.

DESCRIPTION

FIG. 1 is a front perspective view of a display stand showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view thereof showing the display stand in an environment in which it may be used. The dashed broken lines in the figures show portions of the display stand and environment that form no part of the claimed design.

1 Claim, 6 Drawing Sheets
